(57) **CLAIM**

The ornamental design for a protective strip for suitcase, as shown and described.

DESCRIPTION

FIG. 1 is a perspective view of a protective strip for suitcase showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a left side elevational view thereof;

FIG. 7 is a right side elevational view thereof; and,

FIG. 8 is a perspective view of the strip shown on a reduced scale in condition of use on a suitcase, the suitcase being shown in broken lines and forming no part of the claimed design.
